Andrew Morrison

UNITED STATES PATENT OFFICE.

ANDREW MORRISON, OF PITTSBURG, PENNSYLVANIA.

ANTIRAIL-CREEPER.

No. 805,982.

Specification of Letters Patent.

Patented Nov. 28, 1905.

Application filed March 17, 1905. Serial No. 250,532.

To all whom it may concern:

Be it known that I, ANDREW MORRISON, a resident of Pittsburg, Allegheny county, Pennsylvania, have invented a new and useful Antirail-Creeper, of which the following is a full, clear, and exact description, reference being had to the accompanying drawings, forming part of this specification, in which—

10 Figure 1 is a top plan view showing my antirail-creeper in position. Fig. 2 is a sectional end view. Figs. 3 and 4 are views similar to Figs. 1 and 2, showing the modified form; and Figs. 5 and 6 are similar views 15 showing another form.

My invention relates to the devices employed upon railroad-rails for abutting against the ties and prevent endwise creeping of the rails.

20 The object of the invention is to provide a device which is held solely by the thrust of the creeping rail; further, to arrange the device so that the thrust of the rail will act upon the antirail-creeper to bind it more 25 tightly in place and increase its resisting action; also, to provide an antirail-creeper which can be applied without the use of bolts, keys, or other securing means.

The invention further consists in the construction and arrangement of the parts, as 30 hereinafter more fully described and claimed.

In the drawings, referring to the form of Figs. 1 and 2, 2 represents the head, 3 the web, and 4 4 the base-flanges, of the rail resting upon the tie 5. The anticreeping device consists of a sheet-metal plate 6, having clip portions 7 bent over from its diagonally opposite corner portions. The inner edges of these clip portions are spaced at such a distance apart that when the device is turned at an angle to the length of the rail it may be slipped upon the rail by shoving one clip portion into place and then pushing the other end of the clip upwardly and turning the plate. When so turned to position, the clips engage the opposite base-flanges in staggered relation. In order to cause the creeping tendency of the rail, which is in the direction of the arrow, to increase the gripping action, 45 I provide the downwardly-bent lug or abutment portion 8 on the plate, which fits against the face of the tie. It will be noted that this abutment portion is on the side of the rail having the clip farther removed 50 from the edge of the tie than the clip on the

opposite side. The result of this is that when the creeping action is imparted to the rail the lug being closer to the tie than the clip on the lug side of the plate the gripping action will be increased. I therefore obtain 60 a secure grip upon the rail which is proportionate to the force of the creeping action and without the necessity of any bolts or keys.

In the form of Figs. 3 and 4 the form of the 65 plate 6^a is somewhat changed and the clip portions 7^a are bent up from the edge portions of the plate parallel to the tie and at right angles to the edge of the rail. These bent-up portions 7^a are properly notched to 70 fit on the rail-base, and the depending abutment portion 8^a is employed as before.

In the form of Figs. 5 and 6 I show the device as formed of a casting, preferably a malleable-iron casting. In this form the base 6^b 75 is somewhat changed in form, the device being heavier to correspond to the difference in the character of the metal.

The advantages of my invention result from providing a device which is held by the 80 thrust of the creeping rail, also the arranging of the device so that the thrust of the rail will increase the gripping action, and, further, from making the device in a single piece which can be slipped on and then turned to 85 gripping position.

It will be understood that while I show the clips as integral with the base they may be made separately and attached to the base. I 90 prefer the staggered arrangement of the clips, though they may be opposite to each other, provided the clip on the abutment side is further removed from the tie than the abutting portion of the anticreeper.

Other changes may be made in the form 95 and arrangement of the device without departing from my invention.

I claim—

1. An anticreeping device for railroad-rails, having gripping portions on opposite sides, 100 and a tie-abutting portion on one side only, arranged to be located between the rail-gripping portion and the tie at this side of the device; substantially as described.

2. An anticreeping device, having staggered clip portions on opposite sides or ends, 105 and an abutment portion at the end having the clip farthest removed from the tie; substantially as described.

3. An anticreeping device, having a tie- 110

abutting portion at one side, and clip portions at opposite sides spaced apart from the tie; substantially as described.

4. An anticreeping device, having staggered clip portions arranged to slip on the rail when in an angular position relative thereto; substantially as described.

5. An anticreeping device, having integral staggered clip portions; substantially as described.

6. An anticreeping device, having integral staggered clip portions arranged to slip on the tie when in an angle relative thereto, and provided with an abutment portion on the end having the clip farthest removed from the tie; substantially as described.

7. An anticreeping device, consisting of a plate having integral staggered clip portions

at opposite ends and provided with a downwardly-extending abutment portion at the end having the clip farthest removed from the tie; substantially as described.

8. An anticreeping device, consisting of a plate having integral staggered clip portions at opposite ends and provided with a downwardly-extending abutment portion at the end having the clip farthest removed from the tie, said device being arranged to slip on the rail when in an angle relative thereto; substantially as described.

In testimony whereof I have hereunto set my hand.

ANDREW MORRISON.
